UNITED STATES PATENT OFFICE

118,335

DESIGN FOR AN EMBROIDERED COLLAR OR SIMILAR ARTICLE

Ernest W. Freudenberg, Larchmont, N. Y.

Application October 28, 1939, Serial No. 87,911

Term of patent 3½ years

To all whom it may concern:

Be it known that I, Ernest W. Freudenberg, a citizen of the United States, residing at Larchmont, New York, county of Westchester, State of New York, have invented a new, original, and ornamental Design for an Embroidered Collar or Similar Article, of which the following is a specification, reference being had to the accompanying drawing, forming a part thereof.

The figure of the drawing is a plan view of an embroidered collar showing my new design.

The embroidered collar, which is of open work design, is shown on a black surface bringing out the details thereof.

I claim:

The ornamental design for an embroidered collar or similar article, as shown and described.

ERNEST W. FREUDENBERG.
